UNITED STATES PATENT OFFICE.

WILLIAM F. CHINIQUY AND WILLIAM O. WINCH, OF CHICAGO, ILLINOIS.

DEVICE FOR TREATING HAT-BLANKS.

1,111,363.

Specification of Letters Patent. Patented Sept. 22, 1914.

Application filed March 26, 1914. Serial No. 827,302.

To all whom it may concern:

Be it known that we, WILLIAM F. CHINIQUY and WILLIAM O. WINCH, citizens of the United States, residing at Chicago, in the county of Cook and State of Illinois, have invented certain new and useful Improvements in Devices for Treating Hat-Blanks, of which the following is a specification.

10 Our invention relates to the sizing and dyeing of hat-blanks and any operation which involves the treatment of the blanks with a liquid, and also to a device whereby the treatment of said blanks is greatly facilitated.

15 One of the objects of our invention is to carry out the process of dipping the hat-blanks in a manner that is both simple and expeditious and which when properly performed will thoroughly impregnate the blanks and prevent distortion and loss of shape which follows the wetting of certain materials from which hat-blanks are made.

20 Another object of our invention is to construct a suitable holder or form upon which a number of blanks may be superimposed and be retained in proper shape during the dipping thereof and which owing to its particular construction and arrangement will not retard or in any way hinder the impregnation of said blanks.

25 Still another object is to construct the blank-holding device in a manner so that the same may be manipulated to prevent the 30 puckering or bulging of the hat-blank crowns which so often occurs when the hat-blanks are under the process of treatment.

35 These and other objects we accomplish by the means and in the manner hereinafter 40 fully described and as more particularly pointed out in the claims, reference being had to the accompanying drawings forming a part of this specification in which:—

45 Figure 1 is a perspective view of our improved device for carrying out our method of dipping hat-blanks, showing the upper member and hat-blanks raised to better illustrate the manner of assembling the same; Fig. 2 is a transverse section of the 50 assembled device showing a number of hat-blanks under treatment of our process; Fig. 3 is a transverse sectional view of the upper member of our device showing in dotted lines the manner of warping the crown portion thereof to avoid the puckering or bulging of the crown of the hat-blanks.

55 Referring to the drawings, A and B represent the inner and outer members, respectively, of the device for retaining and holding a plurality of hat-blanks C that are to be treated with the usual sizing or dye as the case may be. These members are preferably shaped to conform substantially to the style or mode of the finished blank and comprise the usual crown 4 and 60 brim or flare 5. For this purpose, as will hereinafter be apparent, we prefer to construct these inner and outer members of woven wire material similar to that usually employed for fencing and the like and the 65 mesh of which is of a medium size. This woven wire material we usually cut out of a flat sheet to form a blank of approximately the same size (or larger) than the hat-blank, and it is then shaped or pressed 70 over a form in a manner similar to that employed in the shaping of the hat-blank. When formed to the desired shape the inner member A is placed upon a suitable table and a number of hat-blanks C superimposed 75 upon one another are placed thereon. The upper member B is then placed over the blanks and the inner and outer members are preferably locked or tied firmly together by several straps or ties D. In order 80 to avoid the rough edges of the woven wire material puncturing or injuring the blanks we prefer to turn the edges of the members over or clamp them upon suitable metal binding or edging strips a and b respectively.

85 Before placing the outer member on the blanks we prefer to dent or press the central portion of the crown thereof inwardly as shown in dotted lines in Fig. 3 and after securing the said members together the process of dipping the same may then be commenced. Owing to the wide or open mesh of the wire fabric the fluid of the size or dye will readily 90 impregnate all of the hat blanks as soon as the same has been immersed in the liquid and upon being removed from the sizing or dye vessel, they are hung in a convenient manner to permit them to drip. While the dripping is taking place the members A 95 and B of the device will materially assist in preventing the hat blanks losing their shape when they become sufficiently dried to be removed.

100 If desired the upper member A of the device may be omitted and only the lower or inner member B employed, in which event

it is necessary to tie the hat-blanks C thereon in any suitable manner to prevent the same becoming dislodged from each other or from the frame during the dipping and draining process.

Having described our invention what we claim as new and desire to secure by Letters Patent, is:—

1. A device for use in treating hat-blanks comprising two superimposed members between which a plurality of hat-blanks are adapted to be retained, said members consisting of a reticulated fabric that is shaped to conform to the finished shape of the hat-blanks.
2. A device for use in treating hat-blanks comprising two superimposed members between which a plurality of hat-blanks are adapted to be retained, said members consisting of a reticulated fabric that is shaped to conform to the finished shape of the hat-blanks, and a metallic binding strip extending around the edges of said fabric.
3. A device for use in treating hat-blanks comprising two superimposed members between which a plurality of hat-blanks are adapted to be retained, said members consisting of a reticulated fabric that is shaped to conform to the finished shape of the hat-blanks, and a metallic binding strip extending around the edges of said fabric, and means for securing together the respective edges of said members.
4. A device for use in treating hat-blanks comprising two superimposed members between which a plurality of hat-blanks are

adapted to be retained, said members consisting of a reticulated fabric that is shaped to conform to the finished shape of the hat-blanks, and the outer member of which is adapted to be depressed across the crown portion thereof.

5. A device for use in treating hat-blanks comprising two superimposed members between which a plurality of hat-blanks are adapted to be retained, said members consisting of a reticulated fabric that is shaped to conform to the finished shape of the hat-blanks, the outer member of which is adapted to be depressed across the crown portion thereof, and a metallic binding strip extending around the edges of said fabric.

6. A device for use in treating hat-blanks comprising two superimposed members between which a plurality of hat-blanks are adapted to be retained, said members consisting of a reticulated fabric that is shaped to conform to the finished shape of the hat-blanks, the outer member of which is adapted to be depressed across the crown portion thereof, a metallic binding strip extending around the edges of said fabric, and means for securing together the respective edges of said members.

In witness whereof we affix our signatures in the presence of two witnesses.

WILLIAM F. CHINIQUY.
WILLIAM O. WINCH.
